US00D729333S

(12) **United States Design Patent**
Arnold et al.

(10) **Patent No.:** **US D729,333 S**
(45) **Date of Patent:** **** May 12, 2015**

(54) **NOODLE CAP**

(75) Inventors: **Kent M. Arnold**, Cincinnati, OH (US);
Troy Cooksey, Cincinnati, OH (US);
Bradley M. Ruff, Bowling Green, OH
(US)

(73) Assignee: **Broodle Brands, LLC**, Cincinnati, OH
(US)

(**) Term: **14 Years**

(21) Appl. No.: **29/412,993**

(22) Filed: **Feb. 9, 2012**

(51) LOC (10) Cl. **21-02**

(52) U.S. Cl.

USPC **D21/803**

Primary Examiner — Zenia Bennett(74) *Attorney, Agent, or Firm* — Hasse & Nesbitt LLC; W. Charles Ehlers; Daniel F. Nesbitt(57) **CLAIM**

We claim the ornamental design for a noodle cap, as shown and described.

DESCRIPTION

FIG. 1 is a perspective view of the noodle cap;
FIG. 2 is a bottom left side perspective view thereof;
FIG. 3 is a front elevation view thereof;
FIG. 4 is a back side elevation view thereof;
FIG. 5 is a top view thereof; and,
FIG. 6 is a bottom view thereof.
